VEHICLE DOOR LOCKING DEVICE

Thomas Harrison Clarkson-Jones, Toronto,
Ontario, Canada

Application January 12, 1938, Serial No. 184,516

12 Claims. (Cl. 70—264)

This invention relates to door locking devices and particularly to a door locking system which is especially adaptable for use on motor vehicles.

It is very generally the custom at present to provide locking devices on the doors of a motor vehicle which are capable of locking one door from the outside and the remaining doors from the inside. The practice has been in locking the doors from the inside to simply provide a manual control or handle on each door which when moved to a given position will lock the door. It has been the custom to provide a key controlled device for locking one door from the outside of the vehicle so that when the vehicle was left unoccupied with all the windows in closed condition and the doors other than the key controlled one locked from the inside the car might be fully locked upon locking the key controlled door from the outside.

20 The complete locking operation as now practiced for a four door vehicle entails as many as twelve to fourteen separate locking operations, including the windows, all of which locking operations take a considerable amount of time and trouble. With such a large number of locking operations to be performed, it is very easy to overlook one or more of the necessary operations and thus the vehicle is left an easy prey for thieves. Even if all the doors are locked and 30 the windows closed, an intruder could very easily break a glass pane in one of the doors and reach inside for the handle of the lock in order to unlock the door and enter the vehicle. In those vehicles equipped with "no draft" ventilation windows, it is relatively easy to gain access to the door controls in the interior of the vehicle by forcing these windows with a screw driver or other form of jimmy.

It is the object of this invention to provide a 40 novel system for locking the doors of motor vehicles in one operation and in such a way that the doors cannot be manually unlocked from the inside. The single locking operation for all the doors of the vehicle reduces the amount of time for locking and unlocking the vehicle and positively insures that all doors are locked in one operation. The locking system is preferably operated by key mechanism operable from the outside of the vehicle so that the vehicle may be left in an unoccupied, fully locked condition by 45 simply inserting the key and turning the key the required distance to lock the system.

The novel system herein described cannot be 50 unlocked from the inside of the vehicle except with the use of a key. Therefore it is possible

to leave the windows open or partially open for ventilation without fear of an intruder entering the vehicle by reaching in and releasing the inside control of one of the door locking mechanisms which is now possible for an intruder to 5 do where the conventional door locking devices are used. The novel system as illustrated herein is auxiliary to the customary door latching devices heretofore used and is operable independently thereof, but the system may, if desired, be 10 used as the sole means for locking the doors.

Another important object of this invention is to provide a door locking system especially adaptable for motor vehicles which is constructed in a fool-proof manner and a door locking system 15 characterized by ease and economy in manufacture and use. The elements of which this system is composed are few and simple in construction so that they may be economically manufactured and assembled either in existing motor vehicles 20 or in new vehicles before they have left the manufacturing plant.

Various other objects, advantages and meritorious features of this invention will become more apparent from the following specification, 25 appended claims, and accompanying drawings, wherein:

Figure 1 is a vertical cross-sectional view through the upper portion of a motor vehicle showing the position of the door locking devices 30 on opposite sides of the vehicle and the operating means connecting the devices for joint operation.

Fig. 2 is a top view of a portion of a motor vehicle, broken away for clarity, showing the 35 manner of connecting the door locking devices on opposite sides of the vehicle by a flexible cable.

Fig. 3 is an interior rear view of one of the door locking devices,

Fig. 4 is a cross sectional view of the door 40 locking devices in Fig. 3 taken along line 4—4 in Fig. 3 and showing the manner of assembling the device in a pillar post of a motor vehicle,

Fig. 5 is a horizontal cross-sectional view of 45 the locking device in Fig. 3 taken along line 5—5 in Fig. 3 and also showing the manner of assembling the device in the pillar post of a vehicle,

Fig. 6 is a detail cross-sectional view of one 50 of the rotatable members employed in the locking devices showing its association with a shaft and key operated mechanism therefor,

Fig. 7 is a detail cross-sectional view of another rotatable member employed in one of the locking devices showing the manner of rotatably 55

supporting the same between the walls of a housing,

Fig. 8 is an outside front view of a pillar post of a motor vehicle showing the manner in which 5 the key operated mechanism projects through the pillar post for operation from the outside of the vehicle, and

Fig. 9 is a view of a modification of the invention showing an installation of the locking system 10 on an existing motor vehicle.

The door locking system of the present invention comprises two or more locking devices mounted at remote places in a motor vehicle and operatively connected together for joint operation from a single control. If the motor vehicle in which this system is to be installed has pillar posts on opposite sides of the vehicle against which the unhinged sides of one or more doors abut in closed position, a locking device of the 15 type described herein may preferably be installed in such pillar post for locking the door or doors associated therewith. In motor vehicles of the sedan type having two doors on each side of the vehicle arranged to swing into engagement with 20 a pillar post common to both doors the two doors on each side of the vehicle may be locked by a single locking device. The locking devices of this invention are so constructed that when installed in the pillar posts of such a vehicle 25 they are capable of simultaneously locking the doors on opposite sides of the pillar posts. My invention may, however, be operatively associated with only one door on each side of a vehicle if the construction of the vehicle is of this character. Additional locking devices of the character described herein might be included in the 30 system for locking the cover or door to a trunk compartment or for locking the hood or bonnet over the engine of the vehicle.

40 Referring in detail to the drawings, one locking device in the system, generally indicated at 18, is key operated. The other device or devices in the system are controlled remotely from this key operated device by suitable operating means. 45 The operating means here provided is of the flexible cable type as will be hereinafter described. The other locking device, or devices if more than one such is employed in the system, is generally indicated by the reference numeral 50 12. As shown in Figs. 1 and 2, the locking devices are connected by a cable sheath 14 in which a flexible wire cable 16 is disposed. Bowden type of cable may be employed. Cable 16 operatively connects the two devices 18 and 12 together and 55 is adapted to transmit the key action imposed on the device 10 to device 12. The cable control means is shown extending from one side of the vehicle to the other through the top structure of the vehicle. It is concealed from view between 60 the top panel and the headlining. The cable control may extend, if desired, through the floor or in any other way to connect the locking devices together.

The locking system illustrated herein is incorporated into a vehicle of the sedan type. The locking device 10 is preferably located on the right hand side of the vehicle in a fixed support such as the pillar post 18. The remote device 12 is preferably located in a fixed support on the other side of the vehicle such as in the pillar post 20. Each side of the motor vehicle of the type illustrated herein is provided with two doors arranged so that their unhinged sides abut such pillar posts when the doors are closed. Lock bolts in each device 10 and 12 are capable of be-

ing projected from opposite sides of the pillar posts 18 and 20 to simultaneously engage and lock the doors on opposite sides of the pillar posts.

In Figs. 3, 4 and 5 the interior construction 5 of the locking device 10 is illustrated. The locking device 12 is very similar in construction. In general the description of device 10 will apply to device 12 except as will be hereinafter pointed out.

10 The device 10 comprises a metal casing or housing 22 which is completely closed except for certain openings through which operating elements extend. This housing has a cover plate 24 for permitting access to the interior of the 15 device. The housing is secured to the inner wall surfaces of the pillar post in any suitable way such as by means of projecting metal tongues 26 and screws 28.

A shaft 30 extends across this housing. One 20 end of the shaft is journalled in a trunnion 32 formed by the cover plate. The opposite end of the shaft carries a cylindrical key-operated mechanism 34 whose construction is of the general type customarily used on motor vehicles. Secured to the side wall 36 opposite the cover plate is a hollow cylindrical member 38 which projects coaxially with the shaft and key-operated mechanism and forms an extension to the housing as shown in Fig. 4. This cylindrical extension 25 opens through the outside wall 40 of the pillar post so that the keyhole 42 of the mechanism 34 is exposed to the outside of the vehicle as shown in Fig. 8. The flanges 44 of the doors 45 partially overlap upon the outside wall 40 of the pillar post when the doors are closed. These flanges are here shown as each cut back in a semi-circular manner opposite the keyhole 42 as shown in Fig. 8 to allow the insertion and 30 turning movement of the key. The spacing between these flanges might be such as to avoid necessity of such cut outs.

35 Fixed to the shaft 30 is a member or sheave wheel 46. This member is provided with a grooved periphery 48 which is preferably of a 40 substantial width and formed with a flat bottom 50. A flexible element 52 preferably in the form of a flexible metal strip or tape is partially wound around the sheave wheel 46 and lies within the groove 48 against the flat bottom thereof. The opposite rims of the groove 48 are angularly slotted as at 54 in Fig. 3 to receive a transverse pin 56. The flexible metal tape is secured to pin 56 in the manner shown in this figure. The connection formed by the pin 56 in the angular slot 54 enables the flexible tape to be readily detached when desired. The member or 55 sheave wheel 46, however, is capable when rotated in the direction of the arrow in Fig. 3 to tension the tape 52 and wind the same further 60 around its periphery.

The opposite end of the flexible tape 52 is secured to one end of the flexible cable 16 which is preferably of relatively narrow diameter as shown. The cable 16, as previously explained, 65 is sheathed within a conduit 14 which connects the cable to the locking device 12 in the other pillar post. One end, such as the upper end of the housing 22, is provided with an opening 58 through which the cable 16 is lead. Threaded in 70 this opening is a sleeve 60 forming a guide for the cable 16. The outer threaded end of sleeve 60 is shaped in the form of a cup. A pressed metal rounded cap is fitted snugly over the sheath 14 and is free to move in the cupped bottom 75

of sleeve 60. The freedom of movement of the cap may be as much as 10° from the vertical. A nut 63 threaded to the sleeve is capable of adjusting the height of the sleeve to take up any slack in the cable. The opening 58 and guide sleeve 60 are in tangential alignment with the groove 48 of the rotatable member so that the tape 52 extends therefrom to the cable in a vertical direction.

10 The rotatable member or sheave 46 is capable upon rotation in the direction of the arrow in Fig. 3 to project locking bolts through openings in the opposite sides of the housing 22 so that the bolts project from opposite sides of the pillar posts into locking engagement with the two doors on that side of the vehicle. The locking bolts are similar to one another but irregular in construction. They are preferably mounted for 15 slidable movement across one face of the rotatable member 46 and between that face and the side wall 26 of the housing. The section 66 of each bolt is capable of projection into locking engagement with the door on that side of the pillar post. These sections of the bolts are supported for slidable movement by inwardly extending guides 68 forming an integral part of the housing. As shown the projecting locking sections 66 of the bolts reciprocate in a path diametrical to the axis of rotation of the member 46. 20 Each bolt is jogged intermediate its length to escape past the shaft 30 as it reciprocates. The inner end section 70 of each bolt is slidably guided in its movement by a support 71. The shoulder formed by the jogged central portion of each 25 bolt abuts the shaft 30 and limits the retractible movement of each bolt. Intermediate the length of these bolts there is provided a projecting part 72 which is tensioned to a fixed part of the housing by a coil spring 74. Each coil spring 74 30 yieldingly acts to draw the bolts inwardly to unlocked retracted position.

The rotatable member 46 carries pins 76 which project eccentrically from the face of the member across which the bolts slide. Each pin 76 is associated with one of the locking bolts and is adapted upon rotation of the member 46 to engage the shoulder of the bolt formed by the jogged portion thereof and upon further rotation to force the bolts outwardly from the housing against the tension of the springs 74. When the turning force on the member 46 is released, the coil springs 74 are of sufficient strength to retract their respective bolts and at the same time to rotate the member 46 back to its initial operating position.

The construction of the device generally indicated as 12 is similar to that of device 10 except that the key operated mechanism 34 and the hollow cylindrical extension 38 is omitted. 50 Moreover, the shaft 30 (Fig. 7) corresponding to the shaft 30 in device 10 may be fixed to the opposite walls of the device. The member 82 (Fig. 7) corresponding to member 46 in device 10 may therefore be freely rotatable upon the stationary shaft 30. Except for these differences the description of the device 10 will apply for the description of the remotely controlled device or devices 12 in the locking system.

The operation of the door locking system described herein is as follows: The system of the present invention may function as an auxiliary to the conventional latch mechanism which normally holds the doors closed but not key locked, though if desired such latch mechanism might be omitted. When it is desired to leave the

vehicle in locked condition the doors are closed and the key inserted in the mechanism 34 and turned until the tumblers or wards in the mechanism are in position to lock the mechanism and the shaft 30 associated therewith. In the embodiment of the invention illustrated herein, a key, such as that indicated in dotted outline at 86, is turned in the direction of the arrow in Fig. 4. This rotates shaft 30 and member 46 fixed thereto in the direction of the arrow in Fig. 3. This rotation slides the lock bolts in opposite directions outwardly of the housing so that the sections 66 of the bolts project into locking engagement with the doors on opposite sides of the pillar posts 18.

15 The rotation of the member 46 winds the flexible tape 52 therearound. This movement is transmitted to the cable 16 and by virtue of the latter's connection to the rotatable member 82 in the other locking device 12 causes the lock bolts 20 in the latter device to project and lock the doors on that side of the vehicle. As soon as the key has been turned as far as it is possible it can be withdrawn at which time the tumblers or wards in the locking mechanism 34 lock the shaft 25 30 and member 46 in the position to which they have been turned.

To unlock the system, the key is inserted in the keyhole 42. This causes the tumblers or wards in the locking mechanisms 34 to move to unlocked 30 position. If the operator will lessen his hold upon the key or entirely remove his hand therefrom, the tensioned springs 74 in the devices 10 and 12 will exert sufficient force to retract the bolts and rotate the members 46 and 82 respectively to their initial unlocked position. It is therefore unnecessary for the operator to exert a turning force on the key to unlock the system; the system is capable of unlocking itself as soon as the key is inserted. Thus the system is self-operating in one direction to control the operation of remote door locking devices 10 and 12.

40 Fig. 9 illustrates one manner in which the system may be installed on existing automobiles as an attachment. The locking devices corresponding to 10 and 12 in the previously described embodiment are shown attached to the inside wall of the pillar posts at 10' and 12' respectively. The cable sheath connecting these two devices together is indicated at 14'. Instead of passing through the interior structure of the vehicle, this sheath may be laid upon the floor directly behind the front seat. The usual floor mat may cover the cable to conceal and protect it. The locking bolts in the devices 10' and 12' may be 45 projected into engagement with specially designed bolt receiving structures or striker plates attached to the inside panel of the doors. The operation of this system is similar to that described in the previous described embodiment of 50 the invention.

55 What I claim is:

1. A locking system for motor vehicles having a plurality of doors comprising, in combination, a locking device located adjacent each of said doors at points spaced from one another, cable control means connecting the devices together for joint operation, lock bolts in said devices mounted for movement from projected locking position to withdrawn unlocking position, means including said cable control means for moving said bolts simultaneously to one of said positions, resilient means acting to yieldingly urge said lock bolts in the opposite direction of their movement, manually controlled mechanism operatively con- 65 70 75

- 5 nected into said system and adapted to move
said bolts to one position of their movement
against the pressure of said resilient means and
to releasably hold said bolts in such position,
the resilient means in said devices being of suffi-
5 cient strength to operate the system and re-
turn the bolts in the opposite direction to the
other position of their movement when the bolts
are released from the control of said mechanism.
- 10 2. A locking system for motor vehicles com-
prising, in combination, a plurality of door lock-
ing devices located in a motor vehicle adjacent
the doors thereof at points spaced from one
another, a rotatable member in each of said
15 locking devices, a lock bolt in each device mount-
ed for bodily reciprocal movement from a re-
tracted unlocking position to a projected locking
position, means in each of said devices responsive
to the rotation of said members for bodily mov-
20 ing the lock bolt to one of said positions of its
movement, resilient means in each of said devices
yieldingly opposing the aforesaid movement of
said lock bolts, a flexible cable extending through
the vehicle and operatively connected to the ro-
25 tatable members in said locking devices for joint
operation, manual control means operatively con-
nected in said system and adapted by virtue
of said cable to rotate said members jointly
together to cause simultaneous movement of the
30 lock bolts against the force of said resilient
means to one position of their movement, and
means for releasably locking the system in the
position to which it has been adjusted by said
manual control means and to thus hold the lock
35 bolts against the force of said resilient means,
said resilient means being of sufficient strength
to automatically return the system to its ini-
tial operating position when the locking means
is released whereby the system is self operating
40 in one direction.
- 40 3. In a motor vehicle construction having
doors on opposite sides thereof and fixed pillar
posts against which the doors abut in closed po-
sition, a sheave wheel in each pillar post on op-
posite sides of the vehicle, door locking mecha-
45 nism in each pillar post operable upon rotation
of the sheave wheel in the same pillar post to
be projected into locking engagement with the
adjacent doors, said sheave wheels each having a
rounded peripheral edge of substantial width, a
50 flexible metal strip associated with each rotatable
member and wound around the peripheral
edge of their respective sheave wheels, means
securing one end of the flexible strips to their
55 respective sheave wheels, key operated means
for rotating one of said sheave wheels and thus
wind the flexible strip thereabout, a flexible cable
connecting the unsecured ends of the flexible
strips together and adapted when the key oper-
60 ated member is rotated to tension the cable in
one direction and cause the flexible strip asso-
ciated with the other sheave wheel to rotate the
latter simultaneously.
- 65 4. In a mechanically operated system for lock-
ing and unlocking spaced doors in a structure, a
metal housing completely closed except for a
pair of openings on opposite sides thereof and
an opening in one end thereof, a shaft extending
70 horizontally across the housing and journaled in
opposite side walls thereof, a sheave wheel se-
cured to said shaft for joint rotation therewith,
the peripheral edge of said wheel having a flat-
bottomed groove therearound disposed in sub-
stantial tangential alignment with said opening
75 in the end of the housing, a cable entering said
housing through said end opening, a flexible
metal tape having a section thereof lying within
the peripheral groove of said wheel, means se-
curing one end of said tape to the periphery of
5 said wheel, means securing the other end of the
tape to the end of the cable entering the housing
so that the tape extends from the wheel in a
direction tangential thereto, a pair of lock bolts
in the housing, means supporting said bolts for
10 slidable movement across one face of said sheave
wheel and in opposite directions to one another
from retracted unlocked positions to locked po-
sitions projecting through the openings provided
in the opposite sides of the housing, means ec-
centrically positioned on said face of said sheave
15 wheel adapted to engage said bolts upon rota-
tion of the wheel in one direction and to urge
the bolts in opposite directions to their respec-
tive locked position, and resilient means asso-
ciated with each lock bolt yieldingly urging the
20 bolts to retracted position and adapted when
the sheave wheel is free for turning to auto-
matically retract the bolts and rotate the wheel
back to its initial operating position.
- 25 5. In a motor vehicle construction having a
pair of doors on opposite sides thereof and a
fixed pillar post on each side of the vehicle be-
tween each pair of doors against which the doors
abut in closed position, a metal housing in each
30 pillar post having a pair of openings in the sides
thereof and an opening in one end thereof, a
shaft in each housing extending in a direction
transversely to the vehicle and journaled in op-
posite side walls of its respective housing, said
35 shafts each carrying a rotatable sheave wheel,
a flexible cable extending transversely across the
vehicle and having the opposite end sections
thereof extending through the pillar posts and
through the end openings in said housings,
40 means connecting the opposite ends of said cable
to the sheave wheels in said housing so that
movement of the cable will impose a simultane-
ous rotation to said wheels, a pair of lock bolts
in each of said housings, means mounting said
45 bolts for slidable movement in opposite direc-
tions from retracted unlocked positions to
locked positions projecting through the opposite
side openings of the housing and beyond the
sides of the pillar positions, means on said
50 sheavewheels adapted upon rotation thereof in
one direction to urge the bolts in their respec-
tive housing to locked position projecting beyond
the sides of the pillar posts, one of said housings
having a hollow cylindrical extension in align-
55 ment with the shaft therein and extending
through the outside wall of the pillar post, key
operated means in said cylindrical extension for
turning the shaft and the sheave wheel associ-
ated therewith and for locking the same in the
60 position in which the bolts project from the
sides of the pillar posts, the flexible cable sim-
ultaneously transmitting the action of said key
operated means to the sheave wheel in the other
pillar post, and resilient means associated with
65 said bolts and yieldingly urging the same to re-
tracted position and adapted when the sheave
wheels are free for turning to automatically re-
tract the bolts and rotate the wheels back to
initial operating positions.
- 70 6. A system for simultaneously locking a plural-
ity of doors from a single point of control com-
prising, in combination, a plurality of devices each
associated with a door, a rotatable member in each
device, a lock bolt in each of said devices, means
75 mounting each lock bolt in its respective device

for reciprocal slidable movement from a restricted unlocking position to a locking position projecting from the device, means coupling each lock bolt to the rotatable member in the device with which it is associated and responsive to the rotation of the member in one direction to shift the bolt to one of said positions of its movement, spring means in each device acting upon the lock bolt therein to shift the same in a direction opposite to that produced by the rotatable member, and cable control means extending between each device and connecting the rotatable members therein for joint rotational movement and thus causing all the rotatable members to shift their respective lock bolts simultaneously to one of said positions of their movement, said spring means being of sufficient strength to return the entire system including the bolts, rotatable members and cable control means to the opposite positions of their movements and forming the sole means for accomplishing this return movement.

7. In a vehicle body having a plurality of doors, a door locking system including a locking device associated with each door to lock and unlock the door, a rotatable element in each locking device, at least one member in each of said locking devices movable from a locking position to an unlocking position, spring means in the locking devices yieldingly acting upon the member and continuously urging the same toward one of said positions of their movement, means operatively coupling the rotatable elements in each device with their respective members, said means adapted upon rotation of the elements in one direction to move their respective members against the resistance of the spring means and adapted upon movement of the members in the direction urged by the spring means to cause the elements to rotate in the opposite direction, and a single cable extending between the door locking devices and so connected to the rotatable elements therein that the elements are caused to act jointly to move the members either to locking or unlocking position, and manually controlled means operable to actuate the system against the resistance of said spring means and to automatically releasably hold the system in the operating position opposite to that toward which said spring means urges the system.

8. In a vehicle having a plurality of doors, a door locking system including a locking device for each door mounted in a fixed portion of the vehicle body adjacent to the door with which it is associated, a bodily reciprocal member in each device movable from a door locking position to an unlocking position, an element in each device movable about an axis, means in each device operable upon movement of the element therein in one direction about its axis to cause the member therein to move toward one position of its movement, resilient means in each device opposing said movement of the member and element therein and yieldingly urging the member toward the other position of its movement, a single flexible cable extending between said devices and so connected to the elements therein that when one of the elements is moved against the resistance of said resilient means it simultaneously causes the elements in the other devices to do likewise, manually controllable means for moving an element in one of said devices against the resistance of said resilient means therein and by virtue of the cable to do likewise in the other devices, and means automatically operable to releasably hold

said manually controlled element and by virtue of said cable similar elements in the other devices against the force of said resilient means when the members have been moved to the operating position opposite to that toward which they are urged by the resilient means.

9. In a vehicle having a plurality of doors, a system for locking and unlocking the doors comprising lock mechanism for each door including a rotatable member and a lock bolt operatively associated with the member movable from a locking position to an unlocking position, a single cable extending between the lock mechanisms connecting the rotatable members therein for joint rotation, key controlled mechanism operable to 10 actuate the system including said rotatable members and said cable control means in one direction to move said lock bolts simultaneously from one position of their movement to the other position, and spring means automatically operable to 15 actuate the system including said rotatable members and said cable control means in the opposite direction to return the lock bolts to their first position of their movement.

10. A locking system for an enclosed structure 25 having a plurality of doors for entering and leaving the structure comprising, in combination, a door locking device associated with each door having a lock bolt projectable into locked position and retractable into unlocked position, spring 30 means associated with each bolt urging it toward one position of its movement, tension means operatively connecting said devices for simultaneous movement of their bolts against the action of the spring means, manual control means operable from outside the structure for tensioning said last means and for automatically releasably locking the system when the bolts have been shifted by said tension means against the resistance of their respective spring means to the opposite 35 positions of their movement.

11. A system for simultaneously locking a plurality of doors of a motor vehicle in one operation comprising, in combination, a plurality of devices associated with said doors of the vehicle and arranged adjacent the doors at points spaced apart from one another in the vehicle, a rotatable member in each device, cable control means extending between said devices and connected to the rotatable members therein for effecting joint 45 rotation thereof, a lock bolt in each device, means mounting each lock bolt for movement from a retracted unlocking position to a locking position projecting from the device for engagement with the adjacent door, means coupling each lock bolt to the rotatable member with which it is associated and responsive to the rotation of the member in one direction to shift the bolt to one of said positions of its movement, spring means in 50 said devices yieldingly resisting movement of the lock bolts to said last named position, the spring means in the various devices cooperating together through said cable control means and having sufficient strength to shift the lock bolts to said other 55 position of their movement and at the same time rotate said members to their initial operating position, and means in one of said devices automatically operable to hold the bolt therein and by reason of said cable control means to likewise 60 hold the bolts in the other devices when the bolts are shifted to their position of movement opposite to that toward which they are urged by their respective spring means, said last means being releasable to allow the bolts to be self-oper- 65 70 75

ated in the direction urged by their respective spring means.

12. In a vehicle body having at least one door on opposite sides of the body, a door locking system including a pair of door locking devices mounted in fixed portions of the vehicle body one on each side thereof, said door locking devices each being operable to either one of two positions for locking or unlocking the door on the side of the vehicle body in which it is mounted, a single cable connecting said locking devices for joint operation to either locking or unlocking

position, spring means in said locking devices of a strength sufficient to actuate the devices and the cable jointly to one of said operating positions, manually controllable means operable to actuate the system including the locking devices and the cable to the position opposite to that urged by said spring means, and means operable to releasably hold the system including the locking devices and the cable in said last named position against the force of said spring means. 5 10

THOMAS H. CLARKSON-JONES.
